UNITED STATES PATENT OFFICE.

RICHARD H. FISH, OF FALL RIVER, MASSACHUSETTS.

DOUP HEDDLE.

Application filed May 22, 1925. Serial No. 32,167.

This invention relates to a doup heddle composed of a wire doup, a standard heddle having two eyes therein through which the limbs of the doup pass, and a slotted drop 5 having an eye therein and a slot leading to the eye so that the loops formed at the ends of the limbs of the doup can be placed in the eye of the drop, the main slot in the drop receiving a bar which is carried by a skeleton 10 harness frame, thus providing means whereby the doup can be formed of wire and can be easily and quickly detached from the drop, if the doup should break, so that a new doup can be substituted for the broken one.

15 This invention also consists in certain other features of construction and in the combination and arrangement of the several parts, to be hereinafter fully described, illustrated in the accompanying drawings and 20 specifically pointed out in the appended claims.

In describing the invention in detail, reference will be had to the accompanying drawings wherein like characters denote like 25 or corresponding parts throughout the several views, and in which:—

Figure 1 shows the improvement in use.

Figure 2 is a perspective view of the drop.

As shown in these views, the doup heddle 30 is formed of three parts, the drop 1, the doup 5 and the standard heddle 7, the doup 5 being formed of wire which is bent upon itself to form a substantially U-shaped member, the limbs of which pass through the loops 35 or eyes 8 formed at the central part of the standard heddle 7. Each limb of the doup is formed with a loop 4 and the drop 1 is provided with an eye 2 at its upper end and with a slot 3 which slopes downwardly from 40 the eye through an edge of the drop so that the loops 4 of the doup can be passed through this slot into the eye. Thus the doup is detachably connected with the drop so that it can be easily replaced by a new one 45 if the doup should break. The drop is provided with an elongated slot 6 which is adapted to receive a rod carried by a special harness frame which is enclosed on both sides and ends and contains nothing but the rod. The drop slides on this rod.

50 This invention is mainly designed for leno weaving to secure jacquard patterns on a dobby loom, it being understood that the warp threads pass through the doup.

55 This wire doup is to replace the worsted

doup and bead. In the type of leno for securing the three end leno jacquard effect, the ground makes it possible to weave elaborate patterns having the appearance of cloth woven on a Jacquard loom. The effects are produced on a dobby loom. Only one set of doups is required. The pattern is made from one doup and two ground ends.

During the weaving of the ground cloth, the doup, standard, back and ground harnesses will be raising and falling in plain order. If the extra ground end is taken from the woven cloth, the doup and remaining end will run together. This weave is called the half and return movement.

There is nothing new about this weave, but the figured effect did not find much favor when cotton filling was used. Since artificial silk filling has become the vogue, in the weaving of drapery cloths, the three end 75 leno is a good selling cloth. It is the use of artificial silk in the place of cotton as filling that is giving the cloth a good demand.

The only objectionable feature in the weaving of these cloths is the breaking or 80 wearing out of the worsted doups; they do not last very long and when they commence to break the weaver is kept busy tying-in new doups. Hence, the reason why weavers are not expected to operate many looms, two 85 looms to the weaver being about the limit. With the improved doup a weaver can run six looms and increase the production 15%.

It is to be understood that changes may be 90 made in the construction and in the combination and arrangement of the several parts, provided such changes fall within the scope of what is claimed.

What is claimed is:—

In a device as set forth, the combination 95 with a standard heddle provided with a pair of adjacent loops substantially intermediate the ends of the pedal, of a doup formed of wire and consisting of opposed parts passing through said loops, certain corresponding ends of the opposed parts of the doup having loops, and a slotted drop capable of vertical movement provided with an eye at one end and a slot adjoining and opening 100 into the eye, whereby the loops of the opposed parts of the doup may engage with the eye of the drop through the medium of the slot which adjoins said eye.

In testimony whereof I affix my signature.

RICHARD H. FISH.
